UNITED STATES PATENT OFFICE.

GEORG MERLING AND HUGO KÖHLER, OF ELBERFELD, GERMANY, ASSIGNEES TO
FARBENFABRIKEN VORM. FRIEDR. BAYER & CO., OF ELBERFELD, GERMANY, A
CORPORATION OF GERMANY.

PROCESS OF PRODUCING ISOPRENE.

1,026,691.

Specification of Letters Patent.

Patented May 21, 1912.

No Drawing.

Application filed February 18, 1911. Serial No. 609,444.

To all whom it may concern:

Be it known that we, GEORG MERLING and HUGO KÖHLER, doctors of philosophy, chemists, citizens of the German Empire, residing at Elberfeld, Germany, have invented new and useful Improvements in New Processes of Producing Isoprene, of which the following is a specification.

We have found that isopropenylmethyl-10 carbinol of the formula:

is converted into isoprene of the formula:

by treating it with a dehydrating agent *e. g.*, potassium bisulfate, a mineral acid, zinc chlorid, anhydrous oxalic acid, etc. The isopropenylmethylcarbinol can be obtained by heating the ammonium base obtained from 3-methyl-2-oxy-butyldimethylamin:

In order to illustrate the new process more fully the following examples are given, the parts being by weight:

Example 1: 1 part of isopropenylmethyl-

carbinol is heated with 10 parts of anhydrous oxalic acid in an oil bath to 130-150° C., the isoprene is then condensed in a cooled tube and purified by a fractional distillation.

Example 2: Isopropenylmethylcarbinol is 35 conducted into a porcelain tube which is heated to 130 to 150° C. and which is filled with potassium bisulfate or with native aluminium sesquioxid. The isoprene thus obtained is then condensed and purified as 40 described in Example 1.

We claim:

1. The herein described process for producing isoprene, which process consists in treating isopropenylmethylcarbinol with a 45 dehydrating agent, substantially as described.

2. The herein described process for producing isoprene, which process consists in treating isopropenylmethylcarbinol with oxalic acid, substantially as described. 50

In testimony whereof we have hereunto set our hands in the presence of two subscribing witnesses.

GEORG MERLING. [L. S.]
HUGO KÖHLER. [L. S.]
